CLAIM

The ornamental design for a lifting handle for a toilet seat, as shown and described.

DESCRIPTION

FIG. 1 is a top perspective view of a lifting handle for a toilet seat showing my new design;

FIG. 2 is a top plan view thereof;

FIG. 3 is a front elevational view thereof;

FIG. 4 is a right side elevational view thereof, the left side being a mirror image of the right side;

FIG. 5 is a rear elevational view thereof; and,

FIG. 6 is a bottom plan view thereof.
